UNITED STATES PATENT OFFICE.

FREDERICK AUSTIN, OF CENTRE POINT, IOWA.

DEVICE FOR LOOSENING WELL-DRILLS.

SPECIFICATION forming part of Letters Patent No. 594,772, dated November 30, 1897.

Application filed August 21, 1896. Serial No. 603,538. (No model.)

To all whom it may concern:

Be it known that I, FREDERICK AUSTIN, of Centre Point, Linn county, Iowa, have invented certain new and useful Improvements 5 in Devices for Loosening Well-Drills That May Become Fast in the Drill-Hole While in Operation, of which the following is a specification.

This invention relates to well-drilling machinery; and the object of the invention is to provide simple and efficient means for loosening the drill when it becomes accidentally stuck in the hole. A device for this purpose will be fully hereinafter described and 15 claimed, reference being had to the accompanying drawings, forming a part of this specification, in which—

Figure 1 is a side view of a device embodying the invention as applied to a well-drill. 20 Fig. 2 is a similar view of the same, detached. Fig. 3 is a view of the same in perspective, showing the head thereof opened for the insertion of the drill-rope. Fig. 4 is a top view of the same. Fig. 5 is a coupling connecting 25 the tubular shank of the device with a section of wooden rod.

Similar letters of reference indicate corresponding parts.

In the drilling of deep wells a frequent 30 source of tedious labor and expense is the sticking of the drill in the hole. This is often due to the wedging of a piece of rock over the flaring bit of the drill such as to resist all ordinary means for extracting the drill. 35 My invention is designed to obviate the difficulty very largely by the employment of a device adapted to jar the drill loose in connection with strain upon the drill rope or shank.

Referring to the drawings, A designates 40 the upper end of the drill-rod, to which is usually connected a rope B. The drill-bit (not shown) is supposed to be some distance below.

The apparatus for loosening the drill consists in a rather heavy head C, of iron or 45 steel, provided with an upwardly-extending shank C', adapted to connect with sections of small tubing D or the like. Enough of these sections are connected with the head to give 50 it the requisite weight, and if greater length

is required to carry the shank to the top of the hole sections of wooden rod E are preferably added, the connections of the parts being in any well-known way. At the upper end of the series of sections is a turnbuckle 55 F, to connect with a rope for hoisting and lowering the device in the operation of putting it together and letting it down or taking it out of the well.

For convenience in applying the device to 60 the drill-rope the head is made in two parts hinged together at one side, with interlocking jaws on the other side, with a hole C² provided with a suitable fastening bolt or pin C³.

It is to be understood that the hole in the 65 head is large enough to allow the head to slide freely up and down on the drill-rope, which serves as a guide for it.

The operation of the device is as follows: Tension is applied to the drill-rope by means 70 of the hoisting mechanism above, and while this strain is on the rope an operator, by hand, raises the jarring apparatus and lets it fall forcibly on the upper end of the drill-rod. This heavy blow stretches the drill-rope 75 slightly, loosening the drill downwardly, and the tension of the rope on the recoil draws the drill up again with equal energy. The tension is gradually increased, and the vibratory motion imparted to the drill by the joint 80 action of the blows and tension soon loosens or breaks the obstruction, when the drill may be drawn out of the hole or drilling resumed at pleasure.

It is evident that a rope might be used instead of the sections of wooden rod to raise the head; but to avoid the possibility of a rope winding around the drill-rope and making trouble rods are preferred.

Having thus described my invention, what 90 I claim as new, and desire to secure by Letters Patent, is—

1. The herein-described apparatus for loosening well-drills, consisting of the drill-rope and means for drawing the same taut, a head 95 encircling said rope and adapted to strike the upper end of the drill when dropped, and upwardly-extending sections of rod or tubing connecting with said head, whereby the same may be raised and dropped, as described. 100

2. In a device for loosening well-drills, the combination with the main drill-rope and means for drawing the same taut, of a separable head adapted to encircle the drill-rope
5 when closed, suitable fastenings for the halves thereof, and one or more upwardly-extending sections of rod or tubing connected to one of

the halves of said head, whereby the head may be lifted and dropped, substantially as set forth.

FREDERICK AUSTIN.
